TUBE HOLDER

Conrad Dewey Adelsperger, Bedford, Ohio

Application June 29, 1948, Serial No. 147,272

Term of patent 7 years

(Cl. D4—3)

To all whom it may concern:

Be it known that I, Conrad Dewey Adelsperger, a citizen of the United States and resident of Bedford, Cuyahoga County, Ohio, have invented a new, original, and ornamental Design for Tube Holder, of which the following is a specification, reference being had to the accompanying drawings, forming a part thereof.

In the drawings, Fig. 1 is a front elevational view of a tube holder showing my new design; Fig. 2 is a side elevational view thereof, the opposite side being the same as the side shown; Fig. 3 is a rear elevational view; Fig. 4 is a bottom plan view; and Fig. 5 is a top plan view.

I claim:

The ornamental design for a tube holder, as shown.

CONRAD DEWEY ADELSPERGER.
